EYEGLASS

Reinhardt F. Metzger, Glendale, Long Island,
N. Y.

Application March 13, 1940, Serial No. 323,667

8 Claims. (Cl. 88—53)

This invention relates to eyeglasses and particularly to the structure of and mounting of bows in connection with the lenses of eyeglasses; and the object of the invention is to provide an improved ear engaging bow and a novel mounting or bracket support for the bow to provide a relatively high arrangement of the shank of the bow with respect to each lens of a pair of eyeglasses to maintain proper support and relationship of the lenses with respect to the eyes, while at the same time maintaining a straight line extension of the bow shank from the ear to produce a neat and finished appearance, and further whereby the upwardly extending bow may be adjusted to suit different relationship of eyes and ears of different users; a further object being to provide a structure of the character described wherein means is provided to limit outward swinging movement of the bows while at the same time providing collapsing of the bows upon the lenses in arranging the same in a carrying case or other support; and with these and other objects in view the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a perspective view showing one end portion of a pair of eyeglasses illustrating the mounting of one of my improved bows in connection with a lens of the glasses.

Fig. 2 is a section substantially on the line 2—2 of Fig. 1 on an enlarged scale.

Fig. 3 is a view looking in the direction of the arrows 3 of Fig. 2, indicating the pivot end of the bow in dot and dash lines.

Fig. 4 is a section on the broken line 4—4 of Fig. 2.

Fig. 5 is a sectional view showing a modified form of pivot end construction; and

Fig. 6 is a horizontal sectional view through the bearing portion of the lens engaging part showing another adaptation of my invention.

In the construction of eyeglasses of the type employing ear supporting loops, which are commonly referred to as bows, it has been the common practice to provide a hinge or pivotal mounting of the bow in connection with a bracket secured to the lens or a support for the lens. The

bracket usually had a forked or yoke-shaped bearing for receiving a flattened end of the bow and a pivot pin passed through the bearing and the flattened end of the bow in coupling the parts together, or the bow would have some type and kind of hinge action involving overlapping hinge plates joined by a single pintle. In all such instances the bow extends from the pivotal coupling with the lens at an angle to the point where the bow extends over the ear of the wearer. In certain modern types of eyeglasses of this type and kind, these pivotal mountings have been disposed high on the lens to provide what might be termed a straight extension of the bow from the ear to the point of contact with the eyeglass lens, rather than to have the bow extend downwardly as was the older custom.

It is the purpose of my invention to provide an entirely different form of bow construction and a different mounting of the bow in connection with the lens or bracket attached to the lens so that the bow will extend upwardly substantially parallel to the lens where coupled therewith, and then rearwardly to provide the so-called straight relationship of the bow shank and at the same time provide a strong and durable mounting of the bow in connection with the lens. It will also be apparent that this type of construction will provide means to quickly and easily adjust the bows to the desired relationship on various users having different relative spacings of the eyes and ears.

For the purpose of illustrating certain adaptations of my invention, I have shown in the accompanying drawing at 10 a part of one lens of a pair of eyeglasses. It will be understood that both lenses will be of the same construction and in fact the parts are reversible on each lens. At 11 is shown one of my improved brackets secured to the lens, and at 12 one of my improved bows. The bracket in the construction shown comprises a lens receiving part 13 consisting of inner and outer plates 14 and 15 joined at their outer edges by a cross-member 16 which extends along the peripheral edge 10a of the lens. The plates 14 and 15 are further joined by a screw 17 which passes through the lens 10. The cross-member 16 extends upwardly and downwardly to form long bearings seating upon the edge 10a of the lens 10 as will clearly appear in Fig. 3 of the drawing.

Extending from the central portion of the member 16 and the plate 14 is an inwardly extending bearing 18 having a vertical bore or passage 19 in which is arranged the downwardly

extending terminal end 20 of the bow 12. The downwardly directed end portion 21 of the bow has adjacent the terminal end 20 an enlargement 22 formed in any desired manner and may constitute a sleeve or collar sweated or otherwise secured to the rod forming the bow 12. The enlargement 22 forms a bearing surface 23 which seats upon the pintle bearing 18 of the bracket and is held in this position by any suitable means, such for example as a screw 24, engaging the terminal end 20, and the head 25 of which seats upon a washer 26 which engages the lower surface of the bearing 18.

The enlargement 22 has a projecting finger 27 which projects forwardly when the bow 12 is in the position indicated in Fig. 1. The projection 27 is adapted to strike a stop 28 formed on the plate 14 to limit the outward swinging movement of the bow 12, while at the same time permitting the swinging movement of the bow onto the lenses in placing the eyeglasses in a case or other holder. The stop 28 is disposed above and below the bearing 18 so that the bracket 11 may be used in conjunction with either the right or left lens of a pair of glasses. Thus the one bracket will serve two purposes.

The bow 12 may be of any desired construction as commonly employed in various types and kinds of eyeglasses and composed of any suitable material. However, it is preferred that the material employed is such that the bend at 12a in the bow between the vertical mounting portion 21 and the rearwardly extending shank portion 21a, may be varied to maintain the desired height of the forward end of the shank 21a with respect to the engagement of the ear portion 21b of the bow with the ear of the wearer. This construction is provided to maintain the straight positioning of the shank 21a of the bow rather than the usual downward inclination of the shank as with other eyeglasses of this type and kind. It will also be apparent that in constructing the bows of materials which are not readily susceptible to bending as at 12a, the bows may be made in different sizes to adapt the same for different users, the bows being quickly and easily attached and detached with respect to the brackets.

As another feature of my invention, it will be apparent that the forward end of the bow or the vertical portion 21 thereof is disposed inwardly of the peripheral edge of the lens, especially as viewed from the front of a pair of eyeglasses. This produces a neat and finished appearance of the glasses upon the wearer in that the bows are substantially concealed in the straight forward or front view of the glasses on a wearer. In other words, the bearing portion 18 is substantially within the boundaries of the bracket as will readily appear upon a consideration of Fig. 2 of the drawing.

It will be understood that any suitable means may be provided for retaining the pivot or terminal ends of the bows in connection with the bearings to prevent accidental displacement therefrom. In Fig. 5 of the drawing, one other means is disclosed for accomplishing this result. In the structure shown in this figure the terminal end 20a of the bow is made somewhat longer than the terminal end 20 shown in the other figures, and is tapered as seen at 29 to receive a set screw 30 which is mounted in the bearing 18a. The rounded or beveled inner end 30a of the screw operates in connection with the bevel 29 to hold the surface 23a of the enlargement 22a snugly upon the top of the bearing 18a, while permit-

ting rotation of the bow in the bearing within the limits heretofore referred to. In other words, the structure shown in Fig. 5 is the same as that shown in the other figures with the exception of the different mounting employed for the terminal end 20a.

Aside from producing a novel bearing mounting of a bow in connection with the lens brackets, which amounts to nothing more or less than a shaft or spindle rotating in a bearing, the bend 12a between the shank 21a and the vertical forward end 21 produces what may be termed a spring or yieldable coupling of the bow with the bracket which eliminates stress or strain upon the lenses in the operation of applying and removing eyeglasses in the use thereof. In other words, with the conventional form of eyeglass construction of this type and kind, a substantially rigid and unyielding coupling is provided between the bows and the bracket. Thus all stresses or strains are directly transferred to the eyeglass lens. It will thus be seen that breakage of glasses from this standpoint will be substantially obviated. It will be apparent that my improved bow construction is adaptable for use in connection with eyeglass mountings of various types and kinds, and the illustrations in the accompanying drawing show what might be termed one adaptation and use of the invention.

From a general standpoint, the invention may be said to comprise the provision of a vertically disposed bow end to control and regulate the height of the forward end of the bow with respect to a suitable mounting or coupling with any suitable means for pivotally supporting the vertically disposed front end of the bow in connection with such mounting or coupling.

In the adaptation of the invention as shown in Fig. 6 of the drawing, I have substituted for the securing means 25 of Fig. 4 and the means 30 of Fig. 5, a spring catch device 31 comprising a flat strip of spring metal, one end of which is soldered or otherwise fixedly secured as at 32 to the bearing portion 33 of the lens engaging part 34 which is of the same general construction as the parts shown in the other figures of the drawing. In other words the part 33 is provided with a vertical aperture 35 which receives the terminal end 36 of the bow. The terminal end 36 is recessed as seen at 37 within the bearing substantially in the manner shown in Fig. 5 to receive the inwardly directed free end 38 of the catch device 31. The end 38 is set inwardly from the curved portion of the spring 31 to form a protruding finger piece 39 which will facilitate moving the end 38 out of the recess 37 to permit detachment of the terminal end 36 of the bow from the bearing 33. A radial aperture 40 is provided in the bearing to receive the projection 38. It will of course be understood that upon releasing the spring, the catch end 38 thereof will return to its normal position. The terminal end 36 may be snapped into closed position, or if desired, the member 38 may be drawn outwardly in engaging as well as disengaging the terminal end 36. The bow will have adjacent the terminal end 36 a projection 41 to engage the stop 42 on the part 34 as in the other forms of construction shown. A structure of the type and kind disclosed in Fig. 6 is desirable from the standpoint that the wearer of the glasses may attach and detach the bows without the aid of screwdrivers or other implements which would be otherwise necessary. By making both bows of the same construction, or in other words, hav-

ing the bows interchangeable, the replacement of a bow may be quickly and easily made.

Having fully described my invention, what I claim as new and desire to secure by Letters Patent, is:

1. In eyeglasses of the class described, a lens engaging part, a bow, said bow comprising a horizontal shank portion and a depending coupling portion at the forward end of said shank portion, means pivotally supporting the coupling portion in connection with said part to provide swinging movement of the bow within predetermined limits, and said depending coupling portion having a recess extending longitudinally and opening through the end thereof to receive pin like means for retaining said coupling portion against accidental displacement from said part.

2. A bow for an eyeglass mounting of the class described, said bow comprising an elongated shank portion having a depending end portion extending substantially at right angles to said shank, said depending end portion having an enlargement dividing the same into a short terminal end and a longer portion coaxial with said terminal end, and means whereby said terminal end may be pivotally secured to said eyeglass mounting, said last named means including a threaded recess extending longitudinally and opening through the extremity of said terminal end.

3. A bow for an eyeglass mounting of the class described, said bow having an elongated shank portion and a depending end portion arranged substantially at right angles to said shank, said end portion having a recess extending longitudinally and opening through the extremity thereof, and said recess being adapted for the reception of pin like means in pivotally securing the bow to said mounting.

4. A bow for an eyeglass mounting of the class described, said bow having an elongated shank portion and a depending end portion arranged substantially at right angles to said shank, said end portion having a recess extending longitudinally and opening through the extremity thereof, said recess being adapted for the reception of pin like means in pivotally securing the bow to said mounting, and said end portion having a projection thereon extending in a direction opposed to the direction of said shank and adapted to engage cooperating means on said mounting for limiting the pivotal movement of said bow.

5. A bow mounting for eyeglass lenses, comprising a lens engaging part having a bearing integral therewith, and projecting rearwardly with respect to the plane of a lens supported by said part, said bearing having an aperture extending vertically therethrough, said aperture being arranged substantially in alinement with the portion of said part which engages the periphery of a lens, a bow having a vertically disposed end cooperating with said bearing, the extremity of said end comprising a pintle extending into the aperture of said bearing and said end having an enlargement adjacent said pintle forming an enlarged annular shoulder substantially conforming to and operatively engaging the upper surface of said bearing, means supporting said enlargement in close engagement with said upper surface thereby retaining said bow in connection with said lens engaging part while providing free pivotal movement of said bow, cooperating means on said bow and lens engaging part limiting the extent of said pivotal movement.

6. A bow mounting for eyeglass lenses, comprising a lens engaging part having a bearing integral therewith, and projecting rearwardly with respect to the plane of a lens supported by said part, said bearing having an aperture extending vertically therethrough, said aperture being arranged substantially in alinement with the portion of said part which engages the periphery of a lens, a bow having a vertically disposed end cooperating with said bearing, the extremity of said end comprising a pintle extending into the aperture of said bearing and said end having an enlargement adjacent said pintle forming an enlarged annular shoulder substantially conforming to and operatively engaging the upper surface of said bearing, means supporting said enlargement in close engagement with said upper surface thereby retaining said bow in connection with said lens engaging part while providing free pivotal movement of said bow, cooperating means on said bow and lens engaging part limiting the extent of said pivotal movement, said first named means comprising a threaded recess extending longitudinally of said pintle, and a screw extending upwardly into said recess and cooperating with said bearing for drawing the bow downwardly with respect thereto.

7. A bow mounting for eyeglass lenses, comprising a lens engaging part having a bearing integral therewith, and projecting rearwardly with respect to the plane of a lens supported by said part, said bearing having an aperture extending vertically therethrough, said aperture being arranged substantially in alinement with the portion of said part which engages the periphery of a lens, a bow having a vertically disposed end cooperating with said bearing, the extremity of said end comprising a pintle extending into the aperture of said bearing and said end having an enlargement adjacent said pintle forming an enlarged annular shoulder substantially conforming to and operatively engaging the upper surface of said bearing, means supporting said enlargement in close engagement with said upper surface thereby retaining said bow in connection with said lens engaging part while providing free pivotal movement of said bow, cooperating means on said bow and lens engaging part limiting the extent of said pivotal movement, said first named means comprising a threaded recess extending longitudinally of said pintle, a screw extending upwardly into said recess and cooperating with said bearing for drawing the bow downwardly with respect thereto, said second named means comprising a shoulder on said lens engaging part and a cooperating offset on the enlargement of said bow end extending in a direction opposed to and in substantial alinement with the main portion of said bow.

8. A bow mounting for eyeglass lenses, comprising a lens engaging part having a bearing integral therewith, and projecting rearwardly with respect to the plane of a lens supported by said part, said bearing having an aperture extending vertically therethrough, said aperture being arranged substantially in alinement with the portion of said part which engages the periphery of a lens, a bow having a vertically disposed end cooperating with said bearing, the extremity of said end comprising a pintle extending into the aperture of said bearing and said end having an enlargement adjacent said pintle forming an enlarged annular shoulder substantially conforming to and operatively engaging the upper surface of said bearing, means supporting said enlargement in close engagement with said upper surface thereby retaining said bow in connection with said lens engaging part while providing free pivotal movement of said bow, cooperating means on said bow and lens engaging part limiting the extent of said pivotal movement, said last named means comprising symmetrically arranged portions including shoulders on said lens engaging part above and below said bearing, and a double-faced projection on the enlargement of said bow end in alinement with and in a direction opposed to the main portion of said bow whereby said lens engaging part and bow are each adapted for selective use in either a right or left bow mounting.

9. A bow mounting for eyeglass lenses, comprising a lens engaging part having a bearing integral therewith, and projecting rearwardly with respect to the plane of a lens supported by said part, said bearing having an aperture extending vertically therethrough, said aperture being arranged substantially in alinement with the por-

tion of said part which engages the periphery of a lens, a bow having a vertically disposed end cooperating with said bearing, the extremity of said end comprising a pintle extending into the aperture of said bearing and said end having an enlargement adjacent said pintle forming an enlarged annular shoulder substantially conforming to and operatively engaging the upper surface of said bearing, means supporting said enlargement in close engagement with said upper surface thereby retaining said bow in connection with said lens engaging part while providing free pivotal

movement of said bow, cooperating means on said bow and lens engaging part limiting the extent of said pivotal movement, said first named means comprising an annular groove on the pintle of said bow end and a spring member extending through a transverse aperture in said bearing for operative engagement with said groove, said spring member being shaped for clamping engagement with the outer surface of said bearing, and having protruding means facilitating detachment thereof from said bearing.

REINHARDT F. METZGER.
